CLAIM

The ornamental design for a mixing bowl, as shown and described.

DESCRIPTION

FIG. 1 is a perspective view of a mixing bowl according to the design;

FIG. 2 is a front elevation view thereof, a back elevation view being identical thereto;

FIG. 3 is a right side elevation view thereof, a left side elevation view being identical thereto;

FIG. 4 is a top plan view thereof; and,

FIG. 5 is a bottom plan view thereof.

The portions of the article shown in even broken line form no part of the claimed design.

The portions of the article shown in dash-dot-dash broken lines adjacent unshaded areas represent bounds of the claimed design and form no part thereof.

1 Claim, 5 Drawing Sheets

Related U.S. Application Data

continuation of application No. 29/739,168, filed on Jun. 23, 2020, now Pat. No. Des. 960,642.
